UNITED STATES PATENT OFFICE.

FRANK K. MARTINEK, OF NEW YORK, N. Y.

AUTOMATIC PICOT-CUTTING ATTACHMENT.

Application filed March 27, 1922. Serial No. 547,069.

To all whom it may concern:

Be it known that I, FRANK K. MARTINEK, a citizen of the United States, residing at New York city, in the county of New York

5 and State of New York, have invented certain new and useful Improvements in Automatic Picot-Cutting Attachments, of which the following is a specification.

This invention relates to an automatic 10 picot cutting attachment for a sewing machine and more particularly to a novel and improved removable device adapted to be carried by the presser bar of the machine.

The primary object of the invention is to 15 provide a novel and improved attachment designed for use and cooperating with the conventional type of hemstitching apparatus whereby the threads of the material of the hemstitching are severed to produce a 20 picot edge.

One of the objects of the invention is the 25 construction of an automatic cutting attachment adapted to be mounted on the presser bar for cooperation with the piercer bar bracket including means for rendering the cutting element carried by said attachment inoperative or operative as the material is moved by the continuously movable feed dog.

30 Another object of the invention is the provision of an attachment having a stationary and a movable cutting element cooperating therewith, said attachment being carried by the presser bar so that the cutting edges of 35 the blades will be disposed rearwardly of the needles, including provision whereby one of said blades will be moved for engagement with the piercer bar bracket to effect the cutting of the material as the same is pierced 40 by the piercer.

With these and other objects in view the invention consists in the construction and novel combination of parts hereinafter fully described, illustrated in the accompanying 45 drawing, and pointed out in the subject matter being claimed, it being understood that various changes in the form, proportion, size and minor details of construction may be resorted to without departing from the spirit 50 and scope of the invention.

In the drawings, Figure 1 is a side view showing the invention in its operative position and as mounted on the presser bar.

Figure 2 is a front view.

55 Figure 3 is a bottom view of the attachment as shown in Figure 1.

Figure 4 is an enlarged view partly in section of the attachment showing the cutting blades in their operative and inoperative positions.

Figure 5 is a section taken on the line 5—5 of Figure 4, and

Figure 6 is a further section taken on the line 6—6 of Figure 4.

Figure 7 is a view showing the hemstitching and the picot edge.

Referring now to the drawings wherein like reference characters designate corresponding parts throughout the several views, 5 designates a portion of the machine head and 6 the threaded bearing for the upper end of the presser bar 7, said bar carrying an adjustable collar 8 and a coiled spring 9 disposed between the said bearing and collar as clearly shown by Figure 1 of the drawings. The frame 10 is provided with the removable throat plate 11 and the shuttle 12 is positioned beneath the feed dog 13 which is adapted to receive the respective shoes 14 of the presser foot 15. The presser foot 15 is adapted to be depressed by the spring 16 disposed between the top thereof and the collar 17 mounted on the presser bar 7. A securing collar 18 secured by a set screw 19 permits of the movement of the upper part 80 of the presser foot against the spring 16 and maintains the shoes in their proper position on the work. The piercer bar 20 carries at its lower end an L-shaped piercer bar bracket 21 the lower curved end 22 of which is offset 85 and carries the cloth piercer 23 disposed between the shoes 14 as shown by Figure 2 of the drawing. This structure is old in the art and my invention is directed to an attachment cooperating with the mechanism 90 above described and which will now be set forth in detail.

A slide carriage block 25 substantially rectangular in cross section is provided with a front extension 26, which extension is provided with a recess 27 whereby the slide carriage block 25 may be mounted on the lower end of the presser bar 7 and be secured thereto by the screw 28 thus properly maintaining the attachment on the presser bar 100 and in position adjacent the lower end of the presser foot. The slide carriage block 25 receives a spring controlled plunger or slide carriage 30 therein, said slide carriage having a stop 31 on the top thereof to engage the block 25 to limit the inward movement of said plunger. The plunger slide carriage 105

is provided with a pair of diagonally positioned recesses 32 which receive the springs 33, the said springs being also seated in recesses 34 in the slide carriage block and are 5 adapted to maintain the carriage 30 and its knives in their inoperative position.

The carriage 30 is also provided with a spot hole 35 in one side thereof for receiving a lock pin 36 when the plunger 30 is 10 moved inwardly of the block 25 so as to dispose the cutting elements in their operative position. A lever 37 provided with an extension 38 is pivoted as at 39 in a recess in the side of the slide carriage block, one end 15 of said lever having a slot 40 for engaging a stud 41 on the pin. The opposite end of the lever is enlarged to provide a finger piece 42 whereby said lever may be rocked on its pivot 39 against the resistance of a 20 flat spring 44, which spring is secured at one end to the slide carriage block and at its opposite end to a tension regulating screw 45. Since the slide carriage or plunger 30 frictionally rides within the slide carriage 25, it will be readily seen that as the 25 plunger 30 is forced inwardly, the pin 36 will fall in the spot hole 35 and thus maintain the said plunger in its locked position. However by depressing the lever 37 against 30 the resistance of the spring 44, the pin 36 will of course be withdrawn from the spot hole 35 and consequently the coil springs 33 bearing against the plunger 30 will force 35 the same outwardly to its inoperative position.

Referring now in particular to Figures 4 and 5 it will be observed that the bottom of the slide carriage block 25 is provided with a groove or recess for receiving the top reduced portion 46 of a slide carriage block clamp 47, the same being fastened and secured to the slide carriage 30 by the screw 48. The said block clamp pivotally supports 40 and carries the movable and stationary cutting knives 50, 51, which are held on the pin or screw 52 extending transversely of the said block clamp. The stationary blade or cutting element 51 is provided with a vertical extension 53 within a recess in the 45 front end of the plunger 30 and bearing against the cut away portion 54 of the vertical extension 53, I have provided a spring controlled pin 55, which pin rides within a slot or recess 56 in the upper portion of 50 the plunger 30 and bears against a very small coil spring 57. The front end of the pin extends slightly beyond the inner or front wall of the plunger 30. The pin 55 is provided with a lug 58 bearing against a 55 coil spring 57. The spring 57 urges the pin 55 to the right, see Figure 6, so as to depress the end 60 of the cutting knife 51. It will be observed that the rear end of the stationary blade 51 is cut away at an angle so 60 as to permit of its oscillation on the pivot 65

52, when the plunger is moved forwardly into operative position, the said cut away portion of the blade being adapted to bear against and ride upon the bevelled edge 53^a depending from the bottom of the slide carriage block 25 thus raising the front cutting edge as the plunger 30 moves rearwardly into inoperative position as clearly shown by Figure 4 of the drawing. The pointed front end 60 of the stationary blade is adapted to cooperate with the cutting edge 55^b of the movable blade 50 which is also pivotally mounted on the screw or pin 52 referred to. The movable blade 50, however, is provided with a curved tongue or extension 55^a which is movable to a position beneath the piercer bar bracket so as to be engaged thereby and thus be forced downwardly to engage the material between the shoes 14 thus severing the threads of the material and producing 85 the desired hemstitching and the picot edge. Of course the cutting action of the blades 50 becomes inoperative when the plunger or slide carriage 30 is released as shown in full lines on Figure 4. The movable blade 50 is 90 normally maintained in its raised or elevated position by the spring pressed pin 56 which bears against the upwardly curved rearward end 57^a, it being observed that the said movable blade 50 is also provided with a vertical extension 58^a which may oscillate in the slot 59 in the bottom of the slide carriage block 25. By this construction it will be readily seen that since the cutting edge 55^b of the movable blade is normally maintained 95 in its raised position since the spring pressed pin bears against the curved hook end 57^a, as the plunger or slide carriage is moved forwardly and locks, the curved tongue will be disposed beneath the piercer bar bracket 100 22 so as to be engaged thereby as shown in dotted line, see Figure 4. Consequently the curved tongue will be depressed and the cutting edge 55^b forced through the material, thus severing the material between the shoes 110 14. Of course when the slide carriage or plunger 30 is released or in its inoperative position, the blade 50 will not be engaged by the piercer bar bracket and the machine may continue in the regular sewing, or 115 stitching of the material.

While I have illustrated and described my invention with some degree of particularity, I realize that in practice various alterations therein may be made. I therefore reserve 120 the right and privilege of changing the form of the details of construction or otherwise altering the arrangement of the correlated parts without departing from the spirit of the invention or the scope of the appended 125 claims.

Having thus described my invention, what I claim as new, and desire to secure by United States Letters Patent is:—

1. An automatic picot cutting attachment 130

- in combination with the presser bar and piercer bar bracket of a machine, comprising a carriage block, means for mounting the carriage block on the presser bar so that it may extend rearwardly thereof, a resiliently controlled plunger slideable within the carriage block, means for locking the plunger in its operative position, cutting blades carried by the plunger, one of said blades being engageable by the piercer bar bracket when the slideable plunger is in its locked position.
2. An automatic picot cutting attachment in combination with the presser bar and piercer bar bracket of a machine, comprising a carriage block, a resiliently controlled plunger slideable within the block, means for locking and releasing the plunger to an operative and inoperative position, cutting elements movable with the plunger and means carried by one of the elements for engagement with the piercer bar bracket when the plunger is in its locked or operative position.
3. An automatic picot cutting attachment in combination with the presser bar and piercer bar bracket of a machine, comprising a carriage block, a plunger slideable within the block, resiliently controlled, lever operating means for locking and releasing the plunger to its operative and inoperative positions, cutting elements carried by the plunger, means for normally maintaining the cutting edge of one of said elements in a raised position and means whereby said raised cutting element may be actuated by the piercer bar bracket during its reciprocatory movement.
4. An automatic picot cutting attachment in combination with the presser bar and piercer bar bracket of a machine, comprising a carriage block, a resiliently controlled plunger, slideable within the block, means for maintaining said plunger in its locked, operative position, a stationary and a movable cutting element movable with the plunger, means formed on the movable cutting element for engagement with the piercer bar bracket and resiliently controlled means for rendering said cutting elements inoperative.
5. An automatic picot cutting attachment in combination with the presser bar and piercer bar bracket of a machine, comprising a carriage block, a resiliently controlled plunger slideable within the block, means for locking the plunger in its operative position, a block clamp secured to the bottom of the plunger, a stationary and a movable element pivotally mounted for vertical movement on the block clamp, means for depressing the front edge of the stationary cutting element when the plunger is moved to its operative position, and a curved extension on the movable cutting element for engagement with the piercer bar bracket during its reciprocatory movement.
6. An automatic picot cutting attachment in combination with the presser bar and piercer bar bracket of a machine, comprising a carriage block, a resiliently controlled plunger slideable within the block, means for locking and unlocking the plunger in its operative position, a block clamp and a horizontally pivoted pair of cutting elements carried thereby secured to the bottom of the plunger, means for depressing the front edge of one of the cutting elements, means for maintaining the cutting edge of the second cutting element in its raised position, and means formed on the last mentioned cutting element engageable with the piercer bar bracket during its reciprocatory movement.
7. An automatic picot cutting attachment in combination with the presser bar and piercer bar bracket of a machine, comprising a carriage block, a plunger slideable within the block, lever operated means for locking and unlocking the plunger in its operative position, a depending block clamp secured to the bottom of the plunger, a pair of commonly pivoted cutting elements carried by the block clamp, resilient means bearing against one of said elements when the plunger is in its operative position whereby the front edge is depressed, means engaging the rear end of the second of said elements for normally maintaining the front cutting edge in its raised position and means formed on the last mentioned cutting element for engagement with the piercer bar bracket during its reciprocatory movement.

In testimony whereof I affix my signature.

FRANK K. MARTINEK. [L. S.]
